LE ROY C. CHOWNING, OF CORNING, NEW YORK, ASSIGNOR TO CHOWNING REGULATOR CORPORATION, OF ELMIRA, NEW YORK, A CORPORATION OF NEW YORK.

CONTROL MEANS FOR GAS-PRODUCER REGULATORS.

Application filed December 11, 1919. Serial No. 344,223.

This invention relates to an improvement in control means for gas producer regulators.

The control means forming the subject of my present invention is particularly adapted for use in connection with the type of regulator disclosed in my prior Patent 1,066,252, and which is illustrated in the accompanying drawings.

The primary object of my present invention is to provide a control means which may be operated either through the medium of a hand-controlled electric switch, to effect a shutting off of the steam which controls the gas-making in a gas producer, either before the furnace is reversed, or for any other reason during the course of the operation of the gas producer, such control means also embodying an automatic feature which acts as a sensitizing for the regulator, to effect an operation of the latter upon a sudden building up of the pressure in the gas main, the automatic feature being in its operation independent of the hand-controlled feature of the invention.

The effect of thus shutting off the steam, is to temporarily reduce or stop the gas production, and thus save the gas, which, upon the reversal taking place in a furnace, such as a regenerative steel, or a glass furnace, is ordinarily wasted up the furnace stack during the period of reversal, which period varies ordinarily between two and fifteen seconds.

By thus shutting off the steam slightly in advance of the time that the valve reversal takes place, the gas production is reduced or stopped, thereby leaving the pressure in the main between the producer and the reversing valve, at zero. Although this operation, namely, the shutting off of the steam, does not entirely eliminate the waste, for the reason that the producer stack or main is considerably below atmospheric pressure, the waste being carried away up the stack under a vacuum, nevertheless considerable saving is effected.

The invention will be found to be also particularly of advantageous use in connection with regenerative furnaces which use waste heat boilers, where it is necessary to stop entirely the making of the gas during reversals, since otherwise the gas passes through the boiler mounting, thus forming

in an explosive mixture, sometimes with 55 very disastrous results.

Where open hearth furnaces are used in the steel industry, the gas producers are often located at some distance from the furnaces, and heretofore it has been customary, in order to coordinate the reduction of the gas-making, with the reversal of the furnace, for the melter in charge of the furnace operation, to signal, in some manner, such for instance as by waving the hand to the operator in charge of the gas-house, when changes in the quantity of the gas were required. This system obviously results in a rather haphazard control of the gas production, with respect to the time element 65 involved, because of the impossibility to exactly coordinate the signal system, and thereby eliminate the lag which would necessarily occur between the giving of the signal, and the resultant control of the 70 quantity of gas being produced.

It is an object of this invention to obviate these disadvantages, by providing a control means for the pressure regulator which is at all times under the immediate control 80 of the melter in charge of the furnace operation, whereby he can at will control the making of the gas in the producer.

In carrying out the invention, an electrically controlled valve is used, which, when 85 opened, will admit compressed air to the chamber in which the diaphragm of the pressure equalizing mechanism is mounted, the admission of such air effecting, through the operation of the diaphragm, the closing 90 of the steam valve, and a consequent stoppage of the gas-making in the producer. The valve is controlled from the furnace, so that the melter in charge of the furnace thus has the production of the gas under his 95 control.

The automatic features of the invention, above referred to, provides for a by-pass around the throttle valve of the gas piston which is established between the pressure-regulator and the gas main, such by-pass being controlled by an automatically operating valve, which is set so that it will open upon a sudden up-building of the pressure in the main above its normal point, whereby 100 to allow the pressure of the gas piston to quickly act upon the pressure regulator for operating the same, thereby sensitizing the 105

regulator, and eliminating the lag which would ordinarily occur between the building up of the pressure and the resultant actuation of the regulator by reason of the pressure in the fluid piston having to pass or seep through the throttle valve before reaching and acting upon the regulator.

With these and other objects in view, which will become apparent as the description proceeds, the invention resides in the construction, combination and arrangement of parts hereinafter more fully described and claimed, and illustrated in the accompanying drawings in which like characters of reference indicate like parts throughout the several figures of which,—

Figure 1 represents a diagrammatic vertical sectional view through a gas producer, furnace, and producer regulator and control means therefor, the regulator and control means being drawn to a larger scale than the producer and the furnace, for clearness of illustration.

Figure 2 represents a vertical sectional view through the regulator control means, the control means being shown as disconnected from the pressure regulator, and being rotated on its vertical axis on an angle of 180° with respect to the position shown in Figure 1.

Figure 3 represents a top plan view of the control means.

Referring more particularly to the drawings, the producer is indicated generally at A, the main or stack at B, the furnace-reversing valve is indicated generally at C, and the control lever for shifting the valve is indicated generally at D. These parts are shown diagrammatically, and as their construction and operation is understood by those skilled in the art, a more detailed description of them is deemed unessential.

The type of pressure regulator or maintainer, in connection with which the control means is particularly adapted to be used, is disclosed in Patent 1,066,252, and includes the diaphragm 5, movable vertically within the cover or chamber 6, the skirts or side walls of the diaphragm extending below the normal level of the fluid contained in the chamber. The steam and air is fed to the producer through the steam injectors 7^a as is common practice, the steam for the injectors being fed through the pipe 7, and a piston valve controls the steam, its location being indicated generally at 8. It is not necessary to describe this valve in detail further than to say that it is preferably of the balanced type, to facilitate ease of operation. The piston of the valve is connected with a weighted lever 9 which is operable by a second weighted lever 10, pivoted at 11, and connected to a rod 12, which moves with the diaphragm 5. Thus if the diaphragm is raised, movement is transmitted through

the stem or rod 12, levers 10 and 9, to the piston 8, thus shutting off the air and steam from the producer blowers.

A pipe 13 enters the chamber 6 from below, and terminates under the diaphragm 5 and at a point above the normal liquid level. This pipe connects through pipes 14 and 15 with a pipe 16, which in turn connects to the main B. The pipe connection thus established between the chamber 6 and the main, is of relatively small diameter with respect to the main, and merely serves to transmit the pressure in the main to the under side of the diaphragm. In order that the tars and hydrocarbons will be prevented from being deposited in this pipe connection, there is maintained therein between the diaphragm and the gas main, a piston of a stable gas, such for instance, as atmospheric air or one of the fixed gases, and for this purpose, compressed air from a pipe 17 is introduced into the pipe connection between the diaphragm and the main at the point 18, and in order to prevent the loss of this atmospheric air by leakage or diffusion, a minute quantity of air is uniformly fed to the pipe connection through a suitable valve such as that indicated at 19.

The construction and operation of the parts heretofore described are disclosed more in detail in Patent 1,066,252, and it is thought that a more detailed description is here unnecessary.

The controller for the regulator is indicated generally at E, and includes a casing consisting of upper and lower sections 20 and 21, respectively, secured together in a suitable manner, the section 21 having a top member 22 which forms a partition between the upper chamber 23 and the lower chamber 24, a valve opening 25 being provided in the partition, such opening being controlled by a valve 26. A partition 27 defines the lower limits of the lower chamber 24, and on this partition, a valve stem guide 28 is formed.

The valve stem 29 on which the valve 26 is carried, is slidably mounted in the guide 28, and a spring 30 interposed between the partition 27 and a retainer 31 on the stem, maintains the valve 26 in seated position against the pressure of the air admitted to the chamber 24. Air under approximately ten pounds pressure per square inch is maintained in the chamber 24, through the medium of a pipe 32 connected at one end to the chamber 24 at the point 33, and at its other end connected to the pipe 17 at a point 34 positioned beyond the valve 19 from the pipe 15.

Arranged at the lower end of the casing, is an electro-magnet including a coil 35. One of the wires, namely, 36, forming one branch of the circuit of the coil, has a terminal 37 on the lever of the reversing valve-

control D. The other wire 38, forming the other branch of the circuit, has a split terminal, one branch of which is connected to one plate 39 of the segment along which the lever 37 operates, the other branch being connected at 40 to the other plate of the segment. The segments are insulated from each other as at 41, and when the lever is in alinement with the insulation, in the position shown, the coil is inactive. An armature 42 is carried by the valve stem 29.

The upper chamber 23 of the controller, connects at the point 43 with one end of a pipe 44, the other end of which pipe is in communication with the pipe 14 as at 45, which pipe 14 forms a portion of the pipe connection between the diaphragm chamber 6, and the main B.

The operation of the controller so far described, is as follows,—

When the operator at the furnace shifts the reversing valve control lever to reverse the draft through the flues, the circuit controlling the magnet 35 is closed. The armature 42 is thus attracted, lifting the valve 26 from its seat, against the tension of the spring 30, and the compressed air rushes through the chamber 23, pipe 44, and pipes 14 and 13, into the chamber underneath the diaphragm 5. The latter is thus caused to rise, actuating the levers 10 and 9, and thus closing the steam valve, and hence cutting off the production of gas making in the producer. The valve having been reversed, and the control lever being returned to neutral position, the circuit through the coil is opened, and the spring 30 returns the valve 26 to its seat. The compressed air, as the diaphragm lowers, escapes through the pipe connections 15 and 16 into the gas main B, passing through the throttle stop-cock 46 on its way. As the diaphragm moves into its normal position, the valve 8 is opened, again allowing the delivery of steam to the producer blowers.

The automatic feature of the controller, that is the sensitizing feature for the pressure regulator, comes into operation as a result of the gas pressure in the main building up very rapid from any cause, such for instance as the lowering of the furnace gas control valve F. This feature of the invention includes a valve 47 arranged in the upper portion of the controller, which valve forms normally a closure between the chamber 23 and a smaller chamber 48 thereabove. Communication between the chamber 48 and the pipe 15, forming a section of the pipe line connection between the diaphragm and the main, is established by a pipe 49, which communicates with the pipe 15 at a point above the throttling stop cock 46.

As already pointed out, communication between the chamber 23 and the pipe 14,

at a point below the throttling stop cock 46 is established by the pipe 44. A by-pass around the throttle valve or stop cock is thus established, such by-pass being controlled by the valve 47.

The valve 47 is carried on a stem 50 and is normally held closed by a spring 51, which is set to allow the valve 47 to open when the pressure in the pipe connection between the diaphragm and the main, that is when the pressure in the fluid piston, rises slightly above the normal working pressure. The tension on spring 51 may be varied, by the adjusting nut 52 at the top of the stem 50. Thus the valve 47 may be set to operate at any desired pressure.

The operation of the automatic control feature, or the pressure regulator sensitizing means, is thus controlled by the pressure of the gas in the producer. Upon the building up suddenly of the pressure in the producer or the main, and the consequent increase of pressure in the fluid or air piston which is maintained in the pipe line connection from the main to the diaphragm, the flow of the pressure, being retarded by the throttle valve or stop cock 46, will pass through the pipe 49 into the chamber 48, opening the valve 47 against the tension of its spring, and thus establishing communication around the throttling valve through the chamber 23 and pipe 44 with the diaphragm chamber, and will thus allow immediate response of the diaphragm to the sudden increase of pressure in the main.

Thus the lag which would otherwise occur upon a quick building up of the pressure in the main, between the time of the increase of such pressure, and the time that the pressure regulator responded to such increase, by reason of the necessity of the pressure being retarded by the throttle valve, will be eliminated, and as a consequence, the pressure regulating means will be sensitized, and will respond immediately to any sudden increase of pressure in the main.

Having thus described the invention what is claimed is:—

1. In combination with a gas producer, a uniform pressure-maintaining means including a piston of a fixed gas having a throttle valve therein, a control mechanism for said pressure-maintaining means including a by-pass around the throttle valve, a valve for said by-pass, and yielding means to normally maintain said valve closed against a predetermined pressure of the gas piston, and to permit said valve to open when such pressure increases beyond said predetermined point, whereby to sensitize said uniform pressure-maintaining means.

2. In combination with a gas producer, a

uniform pressure-maintaining means, including a throttle valve, a control mechanism for said pressure-maintaining means including a by-pass for fluid under pressure around the throttle valve, and an automatically operating control means for the by-pass maintaining the by-pass closed against a predetermined pressure of gas in the producer main, and opening the by-pass when the pressure of the fluid increases beyond the said predetermined pressure of the gas in the producer.

3. In combination with a gas producer, and means for maintaining uniform pressure therein, means for regulating the operation of said uniform pressure-maintaining means, a furnace supplied by the producer having a furnace-reversing valve, and a control element common both to the said regulating means and to the said valve.

4. In combination with a gas producer, and means for maintaining uniform pressure therein, means for regulating the operation of said uniform pressure-maintaining means, a furnace supplied by the producer having a furnace-reversing valve, and a control element common both to the said regulating means and the said valve, said regulating means including means for causing said uniform pressure-maintaining means to operate independently of said common control element.

5. In combination with a gas producer, means for maintaining a uniform pressure therein, a furnace supplied by the producer having a furnace-reversing valve, a control lever for said valve, and means also controlled by said lever for controlling the operation of the said uniform pressure-maintaining means.

40 6. The combination of a gas producer, a

pressure-maintaining means therefor, a regulator for said pressure-maintaining means, including a valve to admit air to said pressure-maintaining means, a furnace 45 supplied by the producer having a reversing valve, and operating means for the furnace reversing valve, said operating means also controlling the operation of said air-admitting valve. 50

7. The combination of a gas producer, a pressure-maintaining means therefor, a furnace supplied by the producer having a furnace-reversing valve, operating means for said valve, and a control means for the said 55 pressure-maintaining means, said control means being also controlled by said valve-operating means.

8. The combination of a gas producer, a pressure-maintaining means therefor, a furnace supplied by the producer having a furnace-reversing valve, operating means for said valve, and electrically operative controlling means for said pressure-maintaining means, said electrically operative control 65 means being controlled by the said valve-operating means.

9. The combination of a gas producer, a regulator for maintaining uniform pressure in the producer and including a diaphragm 70 exposed to the pressure in the producer main, a furnace supplied by a producer having a reversing valve, of means for increasing the pressure on the diaphragm of the regulator automatically upon a sudden building 75 up of the pressure in the producer or upon actuation of the reversing valve of the furnace.

In testimony whereof I hereunto affix my signature.

LE ROY C. CHOWNING.
